UNITED STATES PATENT OFFICE

100,946

DESIGN FOR AN ELECTRIC WALL BRACKET

Leo Gudeman, New York, N. Y.

Application April 9, 1936, Serial No. 62,039

Term of patent 7 years

To all whom it may concern:

Be it known that I, Leo Gudeman, a citizen of the United States of America and residing in New York city, New York, have invented a new, original, and ornamental Design for an Electric Wall Bracket, of which the following is a specification, reference being had to the accompanying drawing, forming part thereof.

Figure 1 is a side elevational view of an electric wall bracket, showing my new design;

Figure 2 is a plan view thereof.

Figure 3 is a front elevational view of the same.

I claim:

The ornamental design for an electric wall bracket, as shown.

In testimony whereof I affix my signature.

LEO GUDEMAN.
